UNITED STATES PATENT OFFICE.

ANDERS W. WINBERG, OF SAN JOSE, CALIFORNIA, ASSIGNOR OF ONE-HALF TO E. B. BROWN, OF SAN JOSE, CALIFORNIA.

AUTOMATIC TRAIN-STOPPING DEVICE.

1,187,413.

Specification of Letters Patent. Patented June 13, 1916.

Application filed August 20, 1913. Serial No. 785,705.

To all whom it may concern:

Be it known that I, ANDERS W. WINBERG, citizen of the United States, residing at San Jose, in the county of Santa Clara and State 5 of California, have invented certain new and useful Improvements in Automatic Train-Stopping Devices, of which the following is a specification.

This invention relates to train control systems.

For a full understanding of the invention reference is to be had to the following description and accompanying drawings, in which:—

15 Figure 1 is an end elevation of a locomotive cab equipped with the mechanism. Fig. 2 is a side elevation of the mechanism, the side of the cab being removed. Fig. 3 a detail view of the tripping mechanism. Fig. 20 4 a view showing a mechanism whereby the apparatus may be operated from a point above the track.

Corresponding and like parts are referred to in the following description and indicated 25 in all the views of the accompanying drawings by the same reference characters.

Broadly stated the present invention contemplates the provision of a mechanism supported by the cab of a locomotive and normally maintained with one of its elements in the path of a trip member which is set from the tower of the usual block signaling mechanism. The mechanism is designed when actuated to cut off the supply of steam to 35 the engineer's valve and at the same time apply the air brakes, the air brakes being applied and the steam cut off entirely independent of the usual valves under the control of the engineer for accomplishing such purpose.

It has been found in practice that where the steam supply and the brake mechanism are actuated electrically or by the use of spring-controlled members, the same are rendered inoperative by improper adjustment, by weather conditions, and particularly where springs are used, these structures require constant attention in order that the springs may at all times be under the proper 50 tension to actuate the mechanism.

In the drawings the cab of a locomotive of standard lines is shown equipped with the invention. The air control and throttle which are under the control of the engineer 55 for ordinary use are of the usual construc-

tion and are capable of use entirely independent of the mechanism which constitutes the present invention. The throttle valve 11 is controlled by the lever 12. A cylinder 14 is supported on the boiler within the cab, 60 there being a piston (not shown) arranged within said cylinder and normally maintained toward the front end of the cylinder. This piston has a stem or rod which extends through the rear end 17 of the cylinder and 65 is connected to one terminal of the rocking arm 18. The other terminal of this arm which is pivotally mounted in a manner hereinafter described, is connected to the terminal of a plunger 19 which is of the same 70 construction as the plunger of the throttle valve and actuates a valve 20 in the steam pipe 21. This valve 20 is arranged above the valve 11, that is intermediate the steam supply and said valve 11 whereby when the 75 valve 20 is actuated to cut off the supply of steam the opening of the throttle valve 11 will not admit steam to the cylinders.

The engineer's air controlling valve 22 is supported beneath the cylinder 14, air being 80 supplied to the same by the conduit 23 and conveyed to the brake cylinder by the conduit 24. A second air valve 25 is arranged adjacent the air valve 22. The conduit 23 connects directly with the valve 25, the air 85 being supplied to the valve 22 by the branch pipe 26. The air from the valve 25 passes through a pipe 27 which connects the valve with the pipe 24 which passes to the brake cylinders. Thus it will be noted that the air 90 is controlled by either of the valves 22 or 25. At the same time it will be seen that operating either of the valves when the other is open will not prevent the operation of the 95 brakes.

The valve 25 is controlled by the stem 28 supported for rotation on the valve casing and extending beyond said casing. The arm 18 is fixed on the upper terminal of said stem and when the piston 17 is reciprocated the arm will rotate the stem and accordingly reciprocate the piston 19, the stem 28 constituting the pivot for the arm. Thus the movement of the piston within the cylinder 14 simultaneously cuts off the supply 100 of steam and applies the air brakes.

A pipe 29 is connected to the cylinder 14, said pipe extending downwardly and being connected to a steam conduit 30 which receives steam from the boiler. A valve 31 110

is arranged in said pipe above its juncture with the conduit 30, said valve being actuated by a stem 32 which projects beyond the valve casing. An arm 33 is terminally connected to this valve stem, said arm at its terminal remote from the valve stem being connected to a link 34 which extends downwardly to a point adjacent the road-bed. A shoe 34' is pivotally mounted on the lower end of this link, said shoe carrying a roller 35 which is disposed to contact with an obstruction arranged in the path of the locomotive. While the shoe or trip member is shown as provided with a roller it will be understood that any suitable construction may be used and that instead of the roller illustrated, a flat shoe or a block may be carried on the lower terminal of the shoe. It will be noted that when the roller contacts with an obstruction the link 24 will be moved vertically.

A shaft 36 is disposed transversely of the track beneath the rails, said shaft being formed with cranks to which are pivotally connected plates 37. These plates extend longitudinally of the rails and their terminals are disposed within guides 38 supported on the ties. When the cranks are raised the plates are disposed obliquely with respect to the rails and with their terminals which are connected to the cranks above the rails. When a locomotive approaches the plates the roller 35 of the shoe 34' will ride over the plate carrying the lower terminal 35 of the link 34 downwardly and operating the valve 31. The shaft 36 is arranged at the entrance of each block of the signaling system and is actuated from the tower when the signals are set at danger to raise the cranks and set the plates in the path of the shoe 34'. When a train enters the block with the signals set at danger, the link 34 will be actuated to open the valve 31 and admit steam to the cylinder 14. The steam supplied to the cylinder will move the piston therein toward the rear wall of the cylinder and the arm 18 will be caused to rotate the valve stem 38, opening the valve 25 and releasing the air. The movement of the arm 18 will at the same time close the valve 20 and cut off the supply of steam. It will therefore be seen that when a train enters the block in which the signals are set at danger, the brakes will be immediately applied and the steam cut off. In order that the train may enter the block and that the brakes, etc., will not be actuated, a link 39 is pivotally connected to the shoe 34', constituting a support for said shoe. The link 39 at its upper terminal has a sliding connection with a hand-lever 40, the offset terminal of which is pivotally mounted on the cab. The hand-lever is slotted to receive a pin carried by the link 39 which is

notched and passes through a guide 44, 65 there being a pawl slidably mounted in the guide and engaging in the notches of the lever to prevent its movement. This pawl is actuated by a flexible member 46 which is connected to the grip 47 of the hand-lever 70 40. The engineer controls the operation of the piston by means of a valve 63 which when operated, releases the brakes and restores the steam after the brakes have been applied and the steam cut off. 75

A shaft 48 is mounted adjacent one of the drive wheels of the locomotive, the shaft being provided with a roller 49 which engages the periphery of the adjacent drive-wheel. The shaft is supported by a bracket 80 51 and its terminal which projects through this bracket is provided with a pinion 52. The shaft 53 is disposed vertically of the cab and its lower terminal is provided with a pinion 55 which meshes with a pinion on 85 a longitudinal shaft driven by the pinion 52. The shaft 53 passes through a valve casing 56 and upon its upper terminal is mounted a governor 57. When the locomotive is traveling at an excessive rate of speed 90 the governor 57 which has an operative connection with the valve arranged in the valve casing 56 will open the valve and admit steam to the cylinder 14. The steam is supplied to the valve 56 by means of the conduit 58 which is connected to the pipe 59 which extends within the steam dome. This pipe 59 supplies steam to both of the conduits 30 and 58. The steam admitted to the cylinder 14 will actuate the piston to 100 cut off the steam supply and apply the brakes in the manner heretofore described. It will be noted by this construction that the steam will be cut off and the brakes applied when the locomotive is traveling at an excessive 105 rate of speed.

Attention is called to the fact that various changes may be made in the construction in order that the mechanism may be applied to various types of locomotives and that the 110 specific form of connection between the various elements may be modified to suit different conditions.

In Fig. 4 of the drawings is illustrated a means for actuating the brake applying mechanism from a point above the track. This structure consists of an arm 60 pivotally supported on the roof of the cab and actuated by a trip 61 mounted on the signal tower. By this structure it will be seen that snow and ice will not affect the valve operating mechanism. The structure shown is merely illustrative of one way of accomplishing this actuation of the valves from a point above the track and it will be understood that any suitable structure may be used which will effectually operate the valves which control the actuating piston. 125

Having thus described the invention what is claimed as new is:—

In mechanism of the class described, the combination with a steam supply pipe, a valve arranged therein, an air brake pipe, and a valve arranged therein, of a rock arm connected to the stems of the valves and arranged when rocked to move the same, a source of steam supply, a cylinder in communication with the steam supply and having a piston connected with the rock arm, a valve controlling the supply of steam to the cyl-

inder, an arm connected to the stem of the said valve, a link connected to said arm, an abutment engaging member supported by the link for swinging movement, and manually operable means for adjusting the position of the abutment engaging member. 15

In testimony whereof I affix my signature in presence of two witnesses.

ANDERS W. WINBERG. [L.S.]
